UNITED STATES PATENT OFFICE.

ORLAND A. BORDEN, OF ST. LOUIS, MISSOURI.

STOPPER.

941,302.

Specification of Letters Patent.

Patented Nov. 23, 1909.

Application filed January 18, 1909. Serial No. 473,011.

To all whom it may concern:

Be it known that I, ORLAND A. BORDEN, a citizen of the United States, and resident of St. Louis, Missouri, have invented certain new and useful Improvements in Stoppers, of which the following is a specification.

This invention relates to improvements in stoppers, and has for its object to provide a closure wherein a descriptive circular is contained, which closure is covered by a metallic coupon which must be removed before access can be had to the interior of the receptacle.

A further object is to construct a receptacle having a closure covered with a metallic coupon, in which closure is placed a circular giving proper instructions and information.

In the drawings—Figure 1 is a perspective view of a container showing my improved stopper. Fig. 2 is a top plan view 20 of the same. Fig. 3 is an enlarged detail sectional view showing the general construction. Fig. 4 is a detail top plan view of the coupon after being cut from the stopper.

In the construction of my invention I provide a container 5 of any suitable shape or design, in the upper end of which is formed an opening 6 and a projecting flange 7. Around the flange 7 is securely fastened a cap casing 8 so bent as to form an inwardly projecting cap ledge 9. Upon this flange is supported a recessed cap 10 of sufficient depth to receive a folded circular 11 on which is printed the directions of use, the disposition of the coupon and general information concerning the contents of the container. Over the cap 10 and on its supporting flange 12 is placed a coupon disk 13 so shaped as to be perfectly rigid yet of such material that the same can be cut by a sharp instrument so as to gain access to the circular and cap. The coupon is bound in place by the crimped edge 14 of the cap casing 8. On the coupon may be imprinted the brand, age, quantity, manufacturer and

other information concerning the contents, 45 and the specific feature of this coupon is, to perfectly seal the opening so that the contents can not be tampered with and when once removed (which necessitates cutting) the article is not acceptable. The coupon 50 after being removed may be returned to the merchant and entitles the purchaser to a specified discount. In the cap 10 is secured a ring 15 by which said cap can be handled.

The operation of my invention is as follows: After the container has been properly formed, the casing 8 is securely soldered in place over the opening 6, the upper edge of said casing being originally straight as shown by dotted lines in Fig. 3. The cap 10 60 is then set in place, the circular folded and placed in the cap and on the top of said cap is then placed the coupon 13. After all this has been done, the upper edge of the casing is then crimped inwardly bringing the rolled 65 edge in contact with the coupon as shown in Fig. 3. In this arrangement the cap can not be removed unless the coupon is cut away as previously described.

Having fully described my invention, what 70 I claim is:

A container having an opening; an outwardly projecting flange surrounding said opening; a cap-casing secured upon said flange, having an inwardly projecting cap- 75 ledge and crimped inwardly at its mouth; a recessed cap seated in said ledge; a coupon-disk seated over said recessed cap, and sealed in place by the crimp at the mouth of the cap-casing, substantially as described. 80

In testimony whereof, I have signed my name to this specification, in presence of two subscribing witnesses.

ORLAND A. BORDEN.
